UNITED STATES PATENT OFFICE

EMIL FLORIG AND ALFRED BRACHE, OF NEW YORK, N. Y.

FLYING AEROPLANE CARRIER

Application filed April 19, 1930. Serial No. 445,590.

This invention relates to new and useful improvements in a mid-air aeroplane landing station.

The invention has for an object the provision of a device of the class mentioned which is of simple durable construction, dependable in use and efficient in action and which can be manufactured and sold at a reasonable cost.

10 The invention proposes a lighter than air flying machine, a horizontal platform supported thereon unobstructed for aeroplane landing from above, garage hangars along the sides of said platform and lockers to the 15 front of the platform.

The invention also proposes that said lighter than air flying machine includes a pair of spaced gas bags with said platform between them, and a third gas bag beneath 20 said platform.

The invention also proposes that said third gas bag be detachable and/or adjustable to one side or the other.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a plan view of a device constructed according to this invention.

35 Fig. 2 is a front elevational view of Fig. 1.

Fig. 3 is a side elevation of Fig. 2.

Fig. 4 is a fragmentary enlarged sectional view taken on the line 4—4 of Fig. 1.

40 Fig. 5 is a fragmentary enlarged sectional view taken on the line 5—5 of Fig. 2.

Fig. 6 is a view similar to Fig. 2 but illustrating a modification.

Fig. 7 is a fragmentary enlarged sectional view taken on the line 7—7 of Fig. 1.

The mid-air aeroplane landing station consists of a lighter than air flying machine 10, a horizontal platform 11 supported thereon unobstructed for aeroplane landing from 50 above, garage hangers 12 along the sides of

said platform 11 and lockers 13 to the front of said platform.

The lighter than air flying machine includes a pair of spaced gas bags 14, arranged on the same plane with the said platform 55 11, secured therebetween and serving to hold the gas bags in spaced positions and in firm connection. The lighter than air flying machine also includes a third gas bag 15 between and beneath the gas bags 14 and rigidly held in place by a frame structure 16.

The gas bags 14 and 15 are preferably of cigar shape and parallel with each other. The platform 11 extends substantially the full length of gas bags 14. The third gas 60 65 bag 15 is connected with struts which constitute the said frame 16. Each of the gas bags 14 carry cabins 17 for passengers and for the crew. An elevator 18 leads from the third gas bag 15 to the platform 11. Suitable stairs 19 lead from the cabins of the gas bags 14 to the platform 11.

The frame structure 16 is constructed with suitable openings 16' to allow a free circulation of air around gas bags 14.

75 The horizontal platform 11 consists of flooring formed with a plurality of sliding grates 20 controlled by a handle 20' so as to allow the passing of the air thru the platform 11 when so desired. The garage hangers 12 consist merely in roof structures 21 attached upon the sides of bag structure 14 and extending a short distance over the sides of the platform 11. This arrangement allows one of the sides 22 of the hangers to communicate with the atmosphere upon the platform so that aeroplanes on the platform may be moved beneath the hangers and out into the open. The lockers 13 are closed with doors 23. As shown in the drawing the lockers are formed with cut out parts 24 so that persons may stand therein and look out serving as observation compartments. The lockers are provided with windows 25. On the platform 11 there is a landing marking 26 which consists of a painted longitudinal line connected with a transverse line. This serves to guide aeroplanes landing upon the platform.

100 In Fig. 6, a modification of the invention has been shown in which a means is provided

for detaching or adjusting the third bag 15. This means consists of a frame 28 extended between the gas bags 14 and including a transverse dovetailed groove 29. A slide 30 depends from the groove 29 and is formed with a bottom long T-shaped groove 31.

The third bag 15 is formed with a top track 32 engaging in the T-shaped groove 31. Set screws 33 engage in the sides of slide 30 and abut against the track 32 for locking out into various outside positions. A cable 33' is attached to each side of the slide 30 and extends onto drums 34 in drum chambers 35 attached upon the frame 28 in the vicinity of the gas bags 14. These drums are of conventional design so as to draw and hold the cables in various positions. Dot and dash lines 36 indicate an adjusted position of the gas bag 15.

20 In operation of the device the lighter than air flying machine carries it through the air. Aeroplanes in flight needing repairs may alight upon the platform 11 and they may then be pushed beneath the hangers 12 so that workmen may accomplish suitable repairs. When repairs are finished these aeroplanes may run off of the platform 11 back into flight. Workmen and the crew from the aeroplane landing station may communicate 25 from the various cabins with the landing platform by the elevator 18 and stairs 19. Supplies and other materials may be kept in the lockers 13.

30 In the form shown in Fig. 6, in the event that a busy day is not expected the third gas bag 15 may be detached and the mid-air landing station sent up in the air with only the two gas bags 14. This is intended for use on days in which larger volume of business is 35 not expected. The detaching of the third gas bag is accomplished by merely loosening the screws 33 and sliding the track 32 out of the groove 31.

40 If one side or the other side of the platform 11 is weighted down so that the landing station is at an inclination up in the air, the cables 33' may be drawn in or let out so as to change the position of the third bag 15. Said change of position is indicated by the dot 45 and dash lines 36.

The lower gas bag 15 may also be replaced by two or more bags spaced apart, under and between the upper gas bags 14 for carrying heavier loads.

55 While we have shown and described the preferred embodiment of our invention, it is to be understood that we do not limit ourselves to the precise construction herein disclosed and the right is reserved to all changes 60 and modifications coming within the scope of the invention as defined in the appended claims.

Having thus described our invention, what we claim as new, and desire to secure by 35 United States Letters Patent is:—

1. A mid-air aeroplane landing station, comprising a lighter than air flying machine, a horizontal platform supported thereon unobstructed for aeroplane landing from above, garage hangers along the sides of said platform, and lockers to the front of the platform. 70

2. A mid-air aeroplane landing station, comprising a lighter than air flying machine, a horizontal platform supported thereon unobstructed for aeroplane landing from above, garage hangers along the sides of said platform, and lockers to the front of the platform, said lighter than air flying machine includes a pair of spaced gas bags with said platform between them. 75

3. A mid-air aeroplane landing station, comprising a lighter than air flying machine, a horizontal platform supported thereon unobstructed for aeroplane landing from above, garage hangers along the sides of said platform, and lockers to the front of the platform, said lighter than air flying machine includes a pair of spaced gas bags with said platform between them, and a third gas bag beneath and between said gas bags. 80

4. A mid-air aeroplane landing station, comprising a lighter than air flying machine, a horizontal platform supported thereon unobstructed for aeroplane landing from above, garage hangers along the sides of said platform, and lockers to the front of the platform, said lighter than air flying machine includes a pair of spaced gas bags with said platform between them, and a third gas bag beneath and between said gas bags, a means being also provided for detaching and adjustably communicating the third gas bag in place. 95

5. A mid-air aeroplane landing station, comprising a lighter than air flying machine, a horizontal platform supported thereon unobstructed for aeroplane landing from above, garage hangers along the sides of said platform, and lockers to the front of the platform, said lighter than air flying machine includes a pair of spaced gas bags of cigar shape and parallel with each other. 105

6. A mid-air aeroplane landing station, comprising a lighter than air flying machine, a horizontal platform supported thereon unobstructed for aeroplane landing from above, garage hangers along the sides of said platform, and lockers to the front of the platform, said lighter than air flying machine includes a pair of spaced gas bags of cigar shape and parallel with each other, and cabins supported on said gas bags. 110

7. A mid-air aeroplane landing station, comprising a lighter than air flying machine, a horizontal platform supported thereon unobstructed for aeroplane landing from above, garage hangers along the sides of said platform, and lockers to the front of the platform, said garage hangers 115

comprising an over hung roof extending partially over said platform so as to be above along one side.

8. A mid-air aeroplane landing station, comprising a lighter than air flying machine, a horizontal platform supported thereon unobstructed for aeroplane landing from above, garage hangers along the sides of said platform, lockers to the front of the platform, and means for detaching, adjusting and supporting a third gas bag to a pair of spaced gas bags included in said lighter than air flying machine.

9. A mid-air aeroplane landing station, comprising a lighter than air flying machine, a horizontal platform supported thereon unobstructed for aeroplane landing from above, garage hangers along the sides of said platform, lockers to the front of the platform, and means for detaching, adjusting and supporting a third gas bag to a pair of spaced gas bags included in said lighter than air flying machine, comprising a frame with a transverse groove, a slide in said groove formed with a T-shaped longitudinal groove, a track upon the third bag and engaging in said groove, means for holding said track in place within the groove, and means for holding said slide in various positions along said transverse groove.

10. A mid-air aeroplane landing station, comprising a lighter than air flying machine, a horizontal platform supported thereon unobstructed for aeroplane landing from above, adjustable grates in said platform for controlling the air circulation above and below the said platform, garage hangers along the sides of said platform, and lockers to the front of the platform, said lighter than air flying machine includes a pair of spaced gas bags with said platform between them, and a third gas bag beneath and between said gas bags, said third gas bag is connected to the said spaced gas bags by frame structures which allow the circulation of air around each gas bag.

In testimony whereof we have affixed our signatures.

EMIL FLORIG.
ALFRED BRACHE.
